UNITED STATES PATENT OFFICE.

THOMAS JOHN WOODWARD, OF WEST BROMWICH, ENGLAND, ASSIGNOR TO
THE CHANCE BROTHERS & COMPANY, LIMITED, OF SAME PLACE.

DESIGN FOR PLATE-GLASS.

SPECIFICATION forming part of Design No. 22,566, dated June 27, 1893.

Application filed April 6, 1893. Serial No. 469,356. Term of patent 14 years.

To all whom it may concern:

Be it known that I, THOMAS JOHN WOODWARD, a subject of the Queen of Great Britain, residing at No. 60 Barrow Street, West Bromwich, in the county of Stafford, England, have invented and produced a new and original Design for the Ornamentation of Plate-Glass, of which the following is a specification, reference being had to the accompanying drawings, in which—

Figure 1 is a plan view, showing a portion of a plate glass constructed according to my design; and Fig. 2 is a sectional view taken on the line 2—2 of Fig. 1.

15 In the drawings the letters *a* indicate trian-

gular scrolls and the letters *b* indicate centrally raised or indented triangular pyramids. The space between the triangular scrolls *a* is filled in with conventional representations of leaves *c* and hemispherical projections or indentations *d*.

What I claim is—

A design for plate glass, substantially as herein shown and described.

In testimony whereof I have affixed my signature in presence of two witnesses.

THOMAS JOHN WOODWARD. [L. s.]

Witnesses:

RICHARD SKERRETT,
ARTHUR JOHN POWELL.
